UNITED STATES PATENT OFFICE.

EDWIN J. SCHUYLER, OF WATERBURY, CONNECTICUT, ASSIGNOR TO THE AMERICAN RING COMPANY, OF SAME PLACE.

DESIGN FOR A SPRING FOR GLOVE-FASTENERS.

SPECIFICATION forming part of Design No. 28,533, dated May 3, 1898.

Application filed February 12, 1898. Serial No. 670,150. Term of patent 14 years.

To all whom it may concern:

Be it known that I, EDWIN J. SCHUYLER, a citizen of the United States, residing at Waterbury, in the county of New Haven and State of Connecticut, have invented and produced a new and original Design for a Spring for Glove or Clothing Fasteners, of which the following is a specification, reference being had to the accompanying drawings, in which—

Figure 1 is a plan view of the fastener-spring, and Fig. 2 an edge view of the same.

The leading or material features of my design consist in the substantially circular spring, having parallel slots extending in from one edge and an intermediate slot extending in from the opposite edge and having a central rounded enlargement.

The plate-spring A is approximately circular and has parallel slots *c c'* extending in from one edge and an intermediate or central slot *b* extending in from the opposite edge and having a central rounded enlargement *a*.

What I claim is—

The design for a spring for a glove or clothing fastener, substantially as shown and described.

Signed by me this 9th day of February, 1898.

EDWIN J. SCHUYLER.
